UNITED STATES PATENT OFFICE

OTTO E. SHAW, OF MEADE, KANSAS

MAIL CARRIER RACK

Application filed May 19, 1930. Serial No. 453,685.

The present invention relates to an improved mail carrier for holding mail matter, such as papers and letters in compact form, particularly when the mail man is making delivery.

As the most important and general object of the present invention, it is aimed to provide an improved carrier wherein ratchet means is employed for holding mail matter securely clamped on a base plate.

Another very important object of the invention resides in means whereby the ratchet members may be manually manipulated through out of engagement positions in an easy and convenient manner.

Another very important object of the invention resides in the provision of a device of this nature which is exceedingly simple in construction, inexpensive to manufacture, strong and durable, thoroughly efficient and reliable in use and otherwise well adapted to the purpose for which it is designed.

While the design and construction present illustrated and set forth is deemed preferable, it is obvious that as a result of the reduction of the invention to a more practical form for commercial purposes, the invention is susceptible to various changes.

The invention comprises further features a combination of parts as will be hereinafter set forth and shown in the drawings, wherein:

Figure 1 is a side elevation of the device embodying the features of my invention,

Figure 2 is a top plan view thereof,

Figure 3 is a vertical section taken substantially on the line 3—3 of Figure 1,

Figure 4 is a perspective view of the base plate,

Figure 5 is a perspective view of one of the pawl rods,

Figure 6 is a detail vertical section taken substantially on the line 6—6 of Figure 2,

Figures 7 and 8 are perspective views of the follower plate, and

Figure 9 is a fragmentary detail perspective of the lower end of one of the ratchet bars.

Referring to the drawings in detail it will be seen that the numeral 5 denotes a rectangu-

lar base plate having at its ends depending flanges 6. The base plate 5 is provided with openings 7 adjacent the flanges 6. Numerals 8 denote ratchet bars which extend through the openings 7 and at their lower ends have flattened portions 9 welded or otherwise secured to the inner surfaces of the flanges 6 so that the ratchet bars 8 rise perpendicularly upon the base plate 5.

The numeral 10 denotes a rectangular follower plate having openings 11 in the ends thereof from which depend sleeves 12. The bars 8 extend through the sleeves 12 and the openings 11. Two pair of apertured ears 14 rise from the follower plate 10 and have 65 slidable therethrough a pair of pawl rods 15, the outer ends of which are beveled to engage the ratchet bars 8. The inner ends are 70 standing lips 16 for engagement with the fingers. Springs 17 are disposed about the rods 15 and impinge against the inner ears 14 and against the pins 18 through the rods 75 for holding the rods in engaging position.

By taking the lips 16 between the fingers they may be moved toward each other to disengage the pawl rod from the ratchet bar. An arcuate handle 19 is engaged on the follower plate 10 and is somewhat diagonally disposed.

A mail carrier when using a device of this kind may easily and quickly deliver mail matter since the delivery of the mail matter merely consists in releasing the pawl rod on the follower plate to permit of the extraction of any desired piece of mail matter piled on 85 the base plate so that it may be delivered to its proper destination. As soon as the piece of mail matter is extracted the follower plate may be moved downwardly and the pawl and ratchet mechanism will hold the same in 90 position thereby holding the pile of mail contact in place.

It is thought that the construction, operation, utility and advantages of this invention will now be quite apparent to those skilled in this art without a more detailed description thereof.

The present embodiment of the invention has been disclosed in considerable detail merely for the purposes of exemplification 100

since in actual practice it attains the features of advantage enumerated as desirable in the statement of the invention and the above description.

5 It will be apparent that changes in the details of construction, and in the combination and arrangement of parts may be resorted to without departing from the spirit or scope of the invention as hereinafter claimed or sacrificing any of its advantages.

10 Having thus described my invention, what I claim as new is:

15 A carrier of the class described comprising a base plate having a depending flange at

each end thereof and with a centrally arranged opening adjacent each flange, an up-right rack bar having its lower end passing through said opening and fastened to the flange, teeth on the rack bar formed on the

20 inner face thereof, a follower plate having an opening therein adjacent each end thereof and a depending sleeve connected with the bottom of the plate and surrounding the opening, said rack bars passing through the

25 sleeves and openings, two pairs of upstanding ears on the top of the plate, each pair being arranged adjacent an opening, a bar passing through the ears of each pair and having its outer end beveled to engage the teeth

30 of the rack bar, a handle formed on the inner end of each bar, a spring on each rod and one end bearing against an inner ear, a projection on the rod against which the other end of the spring bears and a curved handle

35 having its ends connected to the top of the follower plate and diagonally arranged to pass over the rods and the inner ears.

In testimony whereof I affix my signature.

OTTO E. SHAW.
